J. P. SEXTON.
PLASTER LATH.
APPLICATION FILED JUNE 28, 1915.

1,205,399.

Patented Nov. 21, 1916.

Inventor:
James P. Sexton,
by *James T. Gaskins*
his attorney.

UNITED STATES PATENT OFFICE.

JAMES P. SEXTON, OF LOS ANGELES, CALIFORNIA, ASSIGNOR TO BUTTONLATH MANUFACTURING COMPANY, A CORPORATION OF CALIFORNIA.

PLASTER-LATH.

1,205,399.

Specification of Letters Patent. Patented Nov. 21, 1916.

Application filed June 28, 1915. Serial No. 36,657.

To all whom it may concern:

Be it known that I, JAMES P. SEXTON, a citizen of the United States, residing at Los Angeles, in the county of Los Angeles, State of California, have invented new and useful Improvements in Plaster-Lath, of which the following is a specification.

This invention relates to improvements in plaster lath, being particularly an improvement upon the plaster lath shown, described and claimed in my Patent No. 1,115,593, dated Nov. 3rd, 1914; and the present invention consists in certain specific particulars of construction hereinafter pointed out.

There are many objects of my present invention among which I may especially mention the following: the provision of a simple, cheap and efficient plaster lath in such form that it may be manufactured efficiently and in commercial quantities.

Another object is the provision of a plaster lath of such design that it is strong and durable in itself and also that the applied superimposed plaster is firmly and permanently bonded thereto, without any liability of the plaster breaking from its bond to the lath or of any part of the finished structure breaking down in any manner.

The details of construction attaining these objects are specifically set forth herein.

A preferred form of the plaster lath and the method are explained herein; and other objects and advantages will be apparent from this specification.

The drawings show preferred forms of my plaster lath and illustrate a preferred form of my method which is described in this specification.

In these drawings, Figure 1 is a transverse section showing my improved plaster lath, Fig. 2 is a face view of the same, Fig. 3 is a similar transverse section showing a double faced form of plaster lath, and Fig. 4 is a diagram illustrating my preferred method of procedure to produce this plaster lath.

I first explain my preferred form of plaster lath and then explain my method of production.

In the drawings I have illustrated a cementitious body at 10, said cementitious body being preferably confined between two form members 11 and 12, said form mem-

bers being face sheets for the cementitious body 10. In the form shown in Fig. 1 the form member or face sheet 11 is plain and imperforate, while in the form shown in Fig. 3, both face sheets 12 and 11^a are shown in identical form, which is hereinafter described, to make a double faced plaster lath for application of plaster upon both faces.

I prefer to form relatively shallow depressions 15 in the face sheet 12, (or both 12 and 11^a as the case may be). These depressions are preferably circular in formation and have sloping sides 16, as is clearly shown in Figs. 1 and 3. In the bottoms of these depressions there are perforations 17 through the face sheet, preferably circular and preferably centrally located in the depressions. The body 10 extends through the circular perforations 16 to form buttons 18. The button is preferably dovetailed in section, as shown in Figs. 1 and 3, and preferably overhangs the edges of the apertures 17, as is illustrated at 19. The button performs primarily the office of affording a key-shaped member around which applied plaster is set, the applied plaster setting under the overhanging edge 20 of the button so as to form a mechanical bond between the plaster lath and the applied superimposed plaster. The overhanging of the button over the edges of the aperture 17 also performs the office of mechanically locking the face sheet 12 onto the cementitious body 10.

It will be particularly noted that the radial space between the overhanging edge 20 of the button and the periphery of the depression is comparatively wide, so as to allow the entry of a large section of applied plaster to the space immediately around the button. This produces a strong construction in which the plaster is not liable to fall away from the plaster lath. It will also be noted that the construction of the depressions with their sloping sides offers an opening for the applied plaster of such shape that there are no points of reduced cross section of the applied plaster around the buttons 18.

In the form shown in Fig. 3, the depression and button formation is duplicated on the opposite side of the lath, providing a construction which will take plaster on both sides and thus providing means for making

a thin plastered partition where such is desired. The buttons are preferably staggered in relation on the opposite sides of the lath.

It is one feature of my present construction that the recesses or depressions 15 are made in such manner that when the face sheet is laid face downward on a flat surface the bottoms of the depressions are held up in proper position while the cementitious base is being applied in the manner herein-after set forth. This action is caused by means of entrapping air in the depressions and also by making the bottoms of the depressions in such form as to resist deformation. I form a bead 21 around the aperture 17 and this bead stiffens the bottom against displacement or deformation.

My preferred procedure for the manufacture of this plaster lath is illustrated by diagram in Fig. 4. (I do not herein attempt to illustrate my complete machinery for carrying my method into effect, but only to illustrate broadly the method itself). A flat member 30, such as a belt, may be made to move horizontally over drums, such as shown at 31. The face sheet 12 is laid face downward on this flat member as shown. It may be fed onto belt 30 from a roll, or in any other manner. The body 10 is applied over the face sheet, as at 10' and the back sheet 11 is then applied. All these operations may take place continuously and simultaneously, the two sheets being laid from rolls and the cementitious substance for the base being continuously applied on the face sheet 12. Immediately the cementitious substance is applied it passes through the perforations 17 as shown at the right in Fig. 4 and the escape of air from the recess 15 is thus shut off, it being understood that the edges of the recess contact all around with the belt or other flat member 30. The air is entrapped in the recess; and this entrapped air, together with the stiffness of the recess bottom, prevents displacement or deformation of the recess bottom. This is an important feature in view of the fact that some pressure must be applied to the body to form it into a uniform layer. This is done by passing under such a member as a roller 32, the distance between the roller and the belt 30 determining the finished thickness of the

plaster lath. The cementitious substance is made of such fluidity that it runs and is pressed through the perforations by just the 55 correct amount to form buttons in the shape herein shown. The dovetailed shape of the buttons is made when the cementitious substance of the button is pressed down on the flat base, flattening or expanding the 60 substance at its base, (its outer end) and thereby forming it as shown. At the same time, and by the same action, the button, as a whole, is made of larger diameter than the perforation through which the cementitious 65 substance has run. As a result of this simple continuous operation the plaster lath is continuously produced in uniform quality. The buttons may vary slightly as to their exact contour but they are generally uniform, of the dovetailed section and of the 70 size and shape shown.

Having described a preferred form of my invention, I claim:

1. A plaster lath, embodying a face sheet 75 having circular depressions of relatively large diameter and small depth and having sloping sides, and having circular perforations at the bottoms of said depressions, and a cementitious base back of said face sheet, 80 said base projecting through the perforations to form a protrusion in each depression, and said protrusion at its periphery clenching over the edges of the perforation.

2. A plaster lath, embodying a face sheet 85 having circular depressions of relatively large diameter and small depth and having sloping sides, and having circular perforations at the bottoms of said depressions, and having a reinforcing bead formed in the 90 sheet around the edge of each aperture in each depression, and a cementitious base back of said face sheet, said base projecting through the perforations to form a protrusion in said depression, and said protrusion 95 at its periphery clenching over the edge of the perforation and over said bead.

In witness that I claim the foregoing I have hereunto subscribed my name this 18th day of June, 1915.

JAMES P. SEXTON.

Witnesses:

JAMES T. BARKELEW,
ELWOOD H. BARKELEW.
